CONCRETE GUN

Richard R. Colburn, Waterloo, Iowa

Application September 9, 1950, Serial No. 183,946

5 Claims. (Cl. 302—49)

1

The present invention relates generally to improvements in the art of shooting or ejecting granular material at high velocity through conduits or nozzles, and relates more specifically to improvements in the construction and operation of gun units for automatically and continuously delivering streams of dry concrete aggregate premixed with Portland cement or the like to remote places of utilization thereof, with the aid of fluid such as air under pressure.

It is frequently desirable in the construction, road building, and other industries, to transport granular material such as dry concrete aggregate and cement in bulk from one locality to another in the form of a high velocity stream or jet with the aid of fluid under pressure. Various types of so-called concrete guns have heretofore been proposed for this purpose, and in my prior Patent No. 2,565,546, granted August 28, 1951, I have disclosed such a gun wherein granular material such as concrete aggregate and cement is shot from a nozzle by means of high pressure air delivered into the inner ends of several annular series of staggered material-laden pockets formed in a revolving rotor, while the outer open ends of the successive revolving pockets are exposed to the aggregate discharge conduit. While the principle of operation involved in the pneumatically actuated gun of this prior patent has proven highly satisfactory and successful, the previous unit itself is rather cumbersome and complicated by virtue of the relative disposition of the material advancing pockets and air admission passages, and the fact that it was rather difficult to effectively seal the rotor against undesirable escape of air after prolonged periods of use without the aid of end valves and other intricate structure.

It is therefore a primary object of my present invention to provide an improved concrete gun involving the successful principle of my said prior patent, but which eliminates the major difficulties encountered in the manufacture and operation of the unit.

Another important object of this invention is to provide a simple, compact, and durable pneumatically actuated granular material ejecting gun, adapted to effectively deliver a constant high velocity jet of various kinds of granular or pulverulent particles in bulk through a conduit or nozzle.

A further important object of the invention is to provide an improved pneumatic gun unit for shooting a continuous stream or jet of granular material such as concrete aggregate and cement

2

through a duct or orifice at high velocity and with the aid of high pressure air, without excessive leakage or escape of the propelling fluid.

Still another important object of my invention is to provide an improved concrete aggregate transporting and ejecting mechanism composed of few simple parts all of which may be readily manufactured and assembled while also being conveniently accessible for inspection and replacement.

An additional important object of the present invention is to provide an automatic gun for shooting dry concrete aggregate and cement or the like with the aid of air under pressure, all parts of which are effectively packed or sealed against leakage, and which is operable at low cost and with minimum attention.

Another more specific object of the invention is to provide a simplified concrete aggregate and cement transfer unit of the type wherein the material is introduced by gravity into the outer open ends of peripheral pockets formed in a revolving rotor, and is ejected from the same ends of the pockets by pneumatic pressure admitted laterally into the inner pocket ends when the advancing pockets have been sealed from the source of supply and have been placed in communication with the discharge conduit or nozzle.

These and other objects and advantages of the invention will be apparent from the following detailed description.

A clear conception of the improved features constituting the present invention, and of the construction and operation of a typical concrete gun embodying the same, may be had by referring to the drawings accompanying and forming a part of this specification wherein like reference characters designate the same or similar parts in the various views.

Fig. 1 is a part sectional view of one of my improved concrete aggregate guns, the section having been taken vertically partly through the center of the material supply hopper and delivery conduit, and partly through one of the annular series of material transfer pockets of the rotor;

Fig. 2 is a part sectional side view of the same gun unit looking toward the final material delivery nozzle or conduit, and with the vertical section taken centrally through the material supply hopper and longitudinally through the upper portion of the rotor; and

Fig. 3 is a part sectional top view of the gun assemblage looking downwardly into the empty material supply hopper, the section having been taken horizontally through the final material

delivery conduit and through the adjacent portion of the rotor.

The gist of my present invention is the provision of an improved gun for automatically delivering a continuous stream of granular or pulverulent bulk material at high velocity through a nozzle or conduit by means of air under pressure delivered into the inner ends of outwardly open material transfer pockets formed in a constantly revolving rotor provided with peripherally open air conducting passages communicable laterally with the inner pocket ends whenever the material laden pockets are exposed to the nozzle conduit and while the invention has been illustrated and described as being especially advantageous for handling concrete aggregate material it is not my desire or intention to unnecessarily restrict the novel features to such usage. It is furthermore contemplated that specific descriptive terms used herein be given the broadest possible interpretation consistent with the disclosure.

Referring to the drawings, the typical pneumatic concrete aggregate conveying unit shown therein, comprises in general, a compact portable main casing or frame 6 adapted to be mounted upon a transporting truck or other suitable support; a rotor 7 provided with a pair of laterally spaced and staggered annular series of material transfer pockets 8, 9 each having an unobstructed outer end at the rotor periphery and an inner end connected laterally with the inner end of an air conducting passage 10 the outer ends of all of which are also open at the rotor periphery midway between the two pocket series; a granular material supply hopper 11 carried by the frame 6 and adapted to deliver material 12 by gravity into the outer open ends of the successive advancing pockets 8, 9 during revolution of the rotor; a discharge housing 13 also carried by the frame 6 and having therein a bifurcated conduit 14 adapted to communicate with the outer open ends of the advancing material laden pockets 8, 9 after they have been sealed from the hopper 11; and a compressed air supply pipe 15 for introducing air under pressure laterally into the inner end of each material laden pocket 8, 9 through its passage 10 whenever the open pocket end has been brought into communication with the conduit 14.

The main casing frame 6 consists primarily of a lower or base section 17 and an upper or cap section 18 firmly but detachably secured to the base section 17 by means of stud bolts 19. The rotor 7 is journaled for rotation about a horizontal axis in bearings 20 clamped between the casing sections 17, 18, and is snugly embraced by a pair of semi-circular resilient liners 21, 22 each of which is provided with a durable metal backing plate 23. These liners 21, 22 are preferably formed of rubber and the backing plates 23 thereof are clamped between the casing sections so as to cause the liners to sealingly engage the rotor periphery, and both liners 21, 22 and plates 23 are provided with upper openings 24, 25 for connecting the outlet end of the hopper 11 with the successive advancing rotor pockets 8, 9 respectively; while the liner 22 and its backing plate 23 are additionally provided with a pair of material discharge side openings 26, 27 for connecting the open ends of the material filled pockets 8, 9 respectively with the bifurcated delivery conduit 14, and with an air inlet opening 28 for simultaneously connecting the successive air conducting passages 10 with the air supply pipe 15. The liner 22 and its backing plate 23

23 are also provided with an elongated lower vent opening 29 adapted to connect each successive pocket 8, 9 and its air passage 14 with the ambient atmosphere through a tube 30 after the material has been ejected from the pocket.

The construction of the rotor 7 is an important feature of my present invention, and this rotor is provided with a peripheral wearing sleeve 32 which coats directly with the resilient liners 21, 22, and is adapted to be constantly revolved at any desired speed by means of a worm wheel 33 housed within the main casing 6 and driven by a worm not shown but which is rotatable by a drive shaft 34 journaled in a bearing 35. The shaft 34 may be driven by an electric motor or the like, and the rotor 7 is rotatable in the direction indicated by the arrow in Fig. 1 and is sealed at the opposite ends of the liners 21, 22 near the bearings 20 by end disks 36. The material transfer pockets 8, 9 of the rotor 7 are preferably radially disposed, and the successive pockets 8 and passages 10 of one annular series are staggered with respect to the successive pockets 9 and passages 10 of the other annular series so that one or more pockets of the two staggered series will always communicate with the hopper 11 and with the discharge conduit 14 and compressed air supply pipe, thus insuring continuity of the stream or jet of material 12 delivered from the unit. The inlet ends of the air injecting passages 10 are all revolvable in a common plane perpendicular to the rotor axis, and all of these passages are equally spaced about the rotor periphery while the peripheral spacing of the pockets 8, 9 is also uniform.

The granular material supply hopper 11 is detachably secured to the upper frame section 18 by resilient clamps 38 coacting with pressure bars 39 attached to the section 18 by stud bolts 40, and these bars 39 also press the liners 21, 22 into sealing engagement with the rotor periphery adjacent to the inlet openings 24, 25. In order to prevent bridging of the material 12 across the downwardly tapered surfaces of the hopper 11, the hopper interior may be provided with one or more agitators 41 carried by a shaft 42 spanning the hopper and journaled in bearings 43 at the opposite sides of the latter. This shaft 42 may be constantly driven from the end of the rotor 7 remote from the worm wheel 33 by a suitable drive confined within a casing 44, and each agitator may be provided with two or more vanes so as to effectively stir the granular material whenever the unit is operating.

The final material discharge conduit housing 13 is likewise detachably secured to the main frame 7, being fastened to an anvil shoe or plate 46 in any suitable manner while the latter is held firmly against the resilient liner 22 adjacent to the openings 26, 27, 28 by other resilient clamping assemblages 38 carried by plates 47 removably attached to the frame 7 by cap screws 48. The housing 13 is also provided with a duct 49 with which the compressed air supply pipe communicates and which is also communicable with the liner opening 28 through a port formed in the anvil shoe 46 as shown in Figs. 1 and 3; and the outer end of the housing 13 may be provided with screw threads 50 for effecting attachment of a hose thereto. Compressed air under high pressure may be delivered through the supply pipe 15 from a compressor or any other suitable source, and the anvil shoe 46 may also be supported upon a cross bar 51 and an auxiliary sealing plate 52 may be provided beneath the anvil

plate and held against the liner 22 by another bar 39 and clamp assemblages 38.

All of the resilient clamping assemblages 38 may be of similar construction, and as shown in Fig. 3, each of these clamps comprises an outer cylindrical casing 54 having therein a plunger 55 urged toward the adjacent portion of the resilient liner 21, 22 by a stiff helical spring 56. When supported by the bars 39, the casings 54 are firmly secured to these bars, and when supported by the plates 47 the casings are likewise rigidly attached thereto as by welding, and all of the assemblages 38 are so disposed that the hopper 11 is effectively sealed from the discharge conduit 14 and this conduit is likewise sealed from the atmosphere at the rotor periphery, thereby positively preventing undesirable escape of compressed air and material while still permitting convenient removal of various parts of the unit for inspection or replacement of worn elements.

When the various elements of the improved concrete gun unit have been properly constructed and assembled as above described, the rotor 7 may be constantly rotated at any suitable speed by power applied through the driving shaft 34 and worm wheel 33, the compressed air supply pipe 15 should be connected to a suitable source of compressed air at approximately one hundred pounds pressure, and the hopper 11 should be kept abundantly supplied with granular material 12 such as concrete aggregate, while the nozzle housing 13 should be attached to a hose or other means for utilizing a jet or stream of the aggregate flowing at high velocity. As the rotor 7 subsequently revolves, the outer open ends of the successive pockets 8, 9 of the two annular series advance past the upper openings 24, 25 respectively, and are filled with batches of the material 12 by gravity. The material 12 thus admitted will not flow into the adjacent passages 10 because of the lateral connection of these passages with the adjacent pockets and the upward disposition of the passage 10 when the pockets 8, 9 are being filled. The revolving agitators 41 will also prevent bridging of the granular material 12 across the hopper 11 and openings 24, 25 and will thus insure complete filling of each advancing pocket 8, 9.

The successive material laden pockets 8, 9 are subsequently advanced along the inner face of the resilient liner 22 and after being sealed from the hopper 11 as illustrated in Fig. 1, these pockets are brought into communication with the discharge conduit 13 through the openings 26, 27. Simultaneously with this establishment of communication between each pocket 8, 9 and the conduit 14, the air inlet passage 10 of the pocket is brought into communication with the compressed air supply pipe 15 through the duct 49 and the opening 28, thereby causing high pressure air to flow into the inner end of the pocket and forcibly ejecting the batch of material 12 therefrom into the conduit 14. Due to the staggered disposition of the pockets 8, 9 of the two series, at least one pocket will be subjected to evacuation at all times, thereby insuring continuity of the jet or stream of material 12 flowing at high velocity through the conduit 14.

After the successive pockets 8, 9 have been thus emptied they advance through a sealing zone 70 along the shoe 46 and breast plate 52, whereupon both the empty pockets and their air supply passages are exposed to the ambient atmosphere through the lower opening 29 and vent tube 30. The empty and completely evacuated successive 75

pockets 8, 9 are thereafter advanced along the resilient liner 21 and are ready for refilling from the hopper 11. The material transporting action is thus carried on continuously and automatically without any attention on the part of an operator other than to start and stop the unit and to maintain an abundant supply of granular material 12 within the hopper 11.

While the clamp assemblages normally maintain an effective seal between the resilient liners 21, 22 and the periphery of the rotor 7, these assemblages may be quickly released to expose the internal structure of the unit. The rotor 7 may be readily removed upon removal of the upper cap section 18 of the main casing, and such release of the section 18 also permits convenient removal and renewal of the liners 21, 22. The resilient clamp assemblages 38 which urge the liners 21, 22 into sealing contact with the rotor periphery will also cause these liners to hug the rotor as they wear down, and furthermore permit the liners to spread slightly in case the pockets 8, 9 receive abnormally hard substances, but the empty passages 10 will normally permit the batches of material to expand slightly in case the pockets are filled too compactly.

From the foregoing detailed description of the construction and operation of a typical portable concrete gun unit embodying my present invention, it will be apparent that I have provided a simple, compact and durable mechanism for effectively producing a high velocity jet or stream of granular material with the aid of high pressure fluid and without excessive leakage of the fluid or loss of the material. The improved gun comprises relatively few sturdy parts which may be readily manufactured, assembled or dismantled, and by locating the inlet ends of the compressed air conducting passages 10 at the rotor periphery, the use of control valves at the ends of the unit is avoided. These passages 10 may obviously be located on either side of their respective pockets 8, 9, but the location thereof between the two pocket series is preferable as it facilitates the manufacture of the rotor 7 and also enhances the sealing effect.

The entire assemblage is so compact that it occupies relatively small space considering the capacity, and by utilizing air pressure at approximately one hundred pounds per square inch, a very high velocity jet is made possible. The present device is therefore not to be confused with a mere feeder for granular material, but is in fact a gun for shooting such material through a nozzle. The improved gun has proven highly satisfactory and successful in actual operation and may be utilized for diverse purposes but especially for the purpose of propelling concrete aggregate and cement.

It should be understood that it is not desired to limit this invention to the exact details of construction and operation of the gun unit herein shown and described, for various modifications within the scope of the appended claims may occur to persons skilled in the art.

I claim:

1. In a gun for shooting a jet of granular materials, a rotor having two laterally spaced annular series of segregated pockets the outer ends of which are open at the rotor periphery and the inner end of each of which communicates laterally with the inner end of a fluid admission passage the opposite ends of all of which are disposed in a common plane perpendicular to the rotor axis and in the space between said two

series and are also open at the rotor periphery between said pocket series, a granular material supply hopper communicable with the open pocket ends of the revolving pockets, means forming a discharge conduit exposable to said open pocket ends, and means disposed within said plane and between said series for admitting fluid under pressure to the inner ends of the advancing material laden pockets through said passages whenever the outer ends of the successive pockets are exposed to said conduit to forcibly eject the batches of granular material from the pockets in the form of a continuous high velocity jet.

2. In a gun for shooting a continuous stream of granular material, a rotor revolvable about a horizontal axis and having several laterally spaced annular series of staggered pockets the outer ends of which are open at the rotor periphery and the inner end of each of which communicates laterally with the inner end of an air admission passage the opposite end of which is also open at the rotor periphery between the two pocket series, a granular material supply hopper communicable during revolution of the rotor with the open ends of the uppermost advancing pockets, means forming a discharge conduit subsequently exposable to the open ends of the successive material laden pockets, and means for admitting air under pressure into said pockets through said passages whenever the open ends of the successive advancing pockets are sealed from said hopper and have been exposed to said conduit.

3. In a gun for shooting a continuous stream of granular materials, a rotor revolvable about a horizontal axis and having a pair of laterally spaced annular series of radial pockets the outer ends of which are open at the rotor periphery and the inner ends of which communicate laterally with the inner ends of air admission passages the opposite ends of which are also open at the rotor periphery between said two pocket series, a granular material supply hopper communicable during revolution of the rotor with the uppermost open pocket ends, means forming a discharge conduit exposable to the open ends of the successive material laden pockets of both series, and common means for admitting air under pressure into the outer ends of said passages whenever the open ends of the successive advancing pockets are sealed from said hopper and have been exposed to said conduit to forcibly eject the batches of granular material from the pockets.

4. In a gun for shooting a jet granular material, a rotor having two laterally spaced annular series of staggered radial pockets the outer ends of which are open at the rotor periphery and the inner ends of which communicate laterally with the inner ends of compressed air admission passages disposed between the two series and the opposite ends of which are also open at the rotor periphery, a supply hopper for delivering granular material by gravity into the successive open pocket ends during revolution of the rotor, means forming a discharge conduit subsequently exposable to the open ends of the revolving pockets, means communicable with the rotor periphery in the space between said series for admitting compressed air into said pockets through said passages whenever the open ends of the pockets are sealed from said hopper and have been exposed to said conduit to forcibly eject the batches of granular material from the pockets through the conduit, and means for subsequently venting the empty pockets.

5. In a gun for shooting a jet of granular material, a rotor having two laterally spaced annular series of staggered radial pockets the outer ends of which are open at the rotor periphery and the inner ends of which communicate laterally with the inner ends of radial compressed air admission passages lying in a common plane midway between the two series and the opposite ends of which are also open at the rotor periphery, a hopper for delivering granular material by gravity into the open ends of the successive pockets, a housing having a discharge conduit exposable to the open ends of the successive material laden revolving pockets and also having a duct disposed midway between said series and communicable with said passages, and means for admitting compressed air in to said pockets through said duct and said passages whenever the open ends of the advancing material laden pockets are sealed from said hopper and have been exposed to said conduit.
